UNITED STATES PATENT OFFICE.

GEORGE A. BOWEN, OF FOND DU LAC, WISCONSIN, ASSIGNOR OF ONE-HALF
TO CHARLES L. MUENTER, OF SAME PLACE.

REFRIGERATOR.

SPECIFICATION forming part of Letters Patent No. 538,724, dated May 7, 1895.

Application filed June 16, 1894. Serial No. 514,752. (No model.)

To all whom it may concern:

Be it known that I, GEORGE A. BOWEN, a citizen of the United States, and a resident of Fond du Lac, in the county of Fond du Lac, 5 and in the State of Wisconsin, have invented certain new and useful Improvements in Refrigerators; and I do hereby declare that the following is a full, clear, and exact description thereof.

10 My invention has for its principal objects to strengthen the ice-box of a refrigerator and to provide for ready removal of the ice-rack, drip-deflector and a water-tank that are normally maintained in said ice-box, whereby the 15 latter may be more easily lifted out of the refrigerator-casing and the cleaning of all the parts facilitated. Therefore said invention consists in certain peculiarities of construction and combination of parts hereinafter 20 set forth with reference to the accompanying drawings and subsequently claimed.

In the drawings, Figure 1 represents a vertical transverse section of a portion of a refrigerator embodying my improvements, the section being taken on line 1 1 of the third figure; Fig. 2, a similar view taken on line 2 2 of the succeeding figure; Fig. 3, a vertical longitudinal section taken on line 3 3 of the first figure; and Fig. 4, a plan view on line 4 4 of the preceding figure, certain of the parts being broken away and others in horizontal section.

Referring by letter to the drawings A represents a refrigerator casing and B the cover for the ice-box portion of the casing, the latter and said cover being of any suitable material and constructed in any suitable manner known in the art.

The ice-box herein shown has its walls turned over at the upper end to form a continuous horizontal flange, that may be stiffened at the corners by reinforcing plates, and when said box is in position for use the flange rests on a corresponding countersunk ledge of the casing. However no claim is made 40 in this case for any peculiarity in the means for suspending the aforesaid ice-box in said casing. As a matter of preferred structural detail the bottom of the ice-box is formed by continuations of the walls bent inward and 45 upward and having their meeting edges sol-

dered, seamed or otherwise joined together whereby a continuous trough is formed around the inside of said box, the latter being given sufficient pitch to insure the flow of water toward an opening b therein that 55 leads to the drain-pipe D of the refrigerator, and I also show the inward and upward turned wall-continuations of such dimensions that a central opening is left in the bottom formed by their union. It is also preferable 60 to have the drip-pan E conform in shape to the lower portion of the ice-box, whereby narrow channels are formed outside the walls of said box and these channels have the necessary pitch to conduct water of condensation 65 to an opening c in said pan over the drain pipe. It is also preferable as a matter of structural detail to have the drip-pan suspended by recurved integral portions d thereof of engaging the edges of upwardly inclined 70 bottom portions of the ice-box.

The ice-box in any form is materially stiffened by means of longitudinal strips F of band-iron herein shown as bolted to walls thereof against spacing-thimbles e, and these 75 longitudinal band-iron strips form supports for transverse strips G of like material from which the deflector H is suspended by rivets or other suitable means, the ends of the latter strips being bent down to come outside the 80 former strips and thereby hold said deflector against lateral displacement. In practice it may be found convenient to so place the spacing thimbles as to have them abut the bent ends of the transverse strips H in such a manner as to prevent longitudinal movement of the aforesaid deflector. It is also possible to omit the thimbles and otherwise space the strips F from the ice-box walls. As herein shown, other band-iron strips I are made fast 85 on the ones G parallel thereto and turned upward at their extremities to form lateral guards for an ice-rack J, but it is possible in practice to omit the strips I and split the ends of the ones G, so that these ends may be bent 90 upward as well as down and thus serve the double function of preventing lateral displacement of the deflector and ice-rack.

From the foregoing it will be seen that the deflector and ice-rack are separate and both 100

of them may be readily removed from the ice-box for the purpose of cleaning.

The ice-rack is preferably of corrugated metal and provided upon its under side with 5 band-iron strips K that extend beyond its edges and serve as guards to prevent it from shifting about, the guards in this instance being longitudinal and the corrugations transverse, but this arrangement may be reversed, 10 and in such a case the ends of the guard-strips would be arranged to oppose the spacing-thimbles above specified.

Adjacent to the drain end of the refrigerator, the ice-box is provided with a transverse 15 strip L of band-iron secured in place by rivets or other suitable means, this strip serving as a support for hooks M cast or otherwise secured to a water-cooler N, and as an advantage of this construction and combination of 20 parts it will be seen that the cooler may be readily lifted out when the faucet thereof is detached, there being no screws or other holding devices that necessitate removal before said cooler can be displaced.

25 By having the cooler so readily removable the weight of the ice-box may be materially lessened when it is desirable to lift the same out of the refrigerator, and it also follows that in order to have access to all parts of said ice- 30 box and cooler, the latter must be removed, otherwise the operation of cleaning cannot be perfectly performed.

In order to obtain the necessary clearance 35 for the faucet-boss of the water-cooler, the ice-rack is cut away at one corner as best illustrated in Fig. 4, and it is to be noted that the

hook supporting the strip L in the ice-box braces the latter in a transverse direction.

Having thus described my invention, what I claim as new, and desire to secure by Letters 40 Patent, is—

1. A refrigerator having its ice-box interiorly provided with supporting strips held in place against spacing-devices, and a deflector having suspending strips that rest on those 45 aforesaid.

2. A refrigerator having its ice-box interiorly provided with supporting strips held in place against spacing devices, a deflector, and suspending strips for the deflector, these latter strips being arranged to rest on those aforesaid and turned down at their extremities to come outside the same. 50

3. A refrigerator having its ice-box interiorly provided with supporting strips held in place against spacing devices, a deflector provided with suspending strips that rest on those aforesaid, and ice-rack guards rising from the deflector-suspending strips. 55

4. A refrigerator having its ice-box interiorly provided with a transverse bracing strip adjacent to one of its ends, and a water cooler having hooks that detachably engage said strip. 60

In testimony that I claim the foregoing I 65 have hereunto set my hand, at Fond du Lac, in the county of Fond du Lac and State of Wisconsin, in the presence of two witnesses.

GEORGE A. BOWEN.
